UNITED STATES PATENT OFFICE.

WILLIAM A. LORENZ, OF HARTFORD, CONNECTICUT.

HERMETIC CLOSURE FOR RECEPTACLES.

1,286,680.

Specification of Letters Patent.

Patented Dec. 3, 1918.

Application filed August 20, 1917. Serial No. 187,050.

To all whom it may concern:

Be it known that I, WILLIAM A. LORENZ, a citizen of the United States, residing at Hartford, in the county of Hartford and State of Connecticut, have invented a new and useful Improvement in Hermetic Closures for Receptacles, of which the following is a specification.

It is common practice to loosely place caps, covers and other closures on cans, jars and similar receptacles containing food and food ingredients to be canned and preserved in prime condition, and then submit the receptacles to the action of a partial vacuum in the exhaust chamber of a hermetic sealing machine which withdraws the air from the interior of the receptacles past the closures and so reduces the interior pressure that the normal atmospheric pressure subsequently exerted on the outside will seat the closures and hermetically seal the receptacles. Some of such closures have been designed to form the seal at the upper edges of the receptacles, some to seal on the exterior and some to seal in the interior of the receptacles. The construction of those closures which have been made to seal on the interior has been such that the withdrawal of all of the air from the inside of the receptacles has been difficult and uncertain, that is, without the exercise of skill and great care these closures would sometimes seat and close the receptacles before all of the air had been withdrawn from the interior, with the result that the closures would be insecurely held, the seal would be imperfect, and the contents of the receptacle subject to the action of the contained atmosphere.

This invention relates to the construction of closures that are designed to close receptacles and form the hermetic air pressure seals between the outer walls of the closures and inner walls of the receptacle. The object of the invention is to provide an interior closure which is so designed that all of the atmosphere will surely be withdrawn from the interior of the receptacle by the exhausting apparatus, and the hermetic seal securely effected, without the exercise of great care and skill in making the closure and manipulating the apparatus.

Figure 1 of the accompanying drawings shows a section of the top of a jar with a cover and gasket placed in the position occupied before the atmosphere is exhausted and the sealing effected. Fig. 2 is a similar

view showing the cover and gasket in sealing position. Fig. 3 shows an edge view of the cover with a part broken away. Fig. 4 shows an edge view of the gasket with a part broken away. Fig. 5 shows a plan of a piece of the gasket.

The receptacle 1 to be sealed, which can be any desired size and shape, may be formed of glass, porcelain or other suitable material. Around the interior, a short distance below the mouth of the receptacle, is a narrow shoulder 2. This shoulder is desirably provided by curving inward the inner wall of the rim of the receptacle.

The cover 3, which is somewhat smaller in diameter than the recess in the mouth of the receptacle above the shoulder, may be made of glass, porcelain or any other suitable material. Around the periphery near the inside face of the cover is a concave recess 4. Fitted in the concave recess about the cover is a flexible gasket 5. This gasket, which is desirably made of rubber composition, is shaped so that the outer corner 6 of the inner face will be thin or sharp and quite yielding. It is preferred to form one or more shallow grooves 7 in the outer periphery of the gasket, and although these grooves may be of any desired outline, they preferably are narrow at the top and a little wider at the bottom.

In practice the receptacle is filled to, or near to, the shoulder with the substance to be preserved, then the cover with the yielding gasket fitted about it is placed loosely in the recess in the mouth of the receptacle. When the cover and gasket are thus located the sharp, thin, flexible edge of the outer corner of the gasket rests upon the rounded wall above the shoulder, as shown in Fig. 1. The receptacle, with others, closed in this manner is placed in the hermetic machine commonly employed, and as the air is exhausted from the chamber of the machine the air is drawn out from the interior of the receptacle through the air-escape grooves formed in the periphery of the flexible gasket. After the proper degree of vacuum has been established the cover is pressed downwardly so as to compress the gasket upon the sealing seat. When the cap is forced down the flexible gasket is so compressed by the concave wall of the sealing seat that the small grooves in the periphery of the gasket are closed and the space between the cover and wall of the receptacle

tightly closed and effectually sealed, as shown in Fig. 2. Air is then admitted to the machine in the usual way and the normal atmospheric pressure holds the cover down upon the gasket and establishes a secure hermetic closure of the receptacle.

The cover is before sealing supported by the thin, sharp flexible edge of the corner of the gasket which rests upon the curved wall of the recess so that during the exhausting operation air will draw out past the thin flexible supporting corner of the gasket, and after sealing the flexible gasket fills all the space between the wall of the mouth of the receptacle and the edge of the cover.

A receptacle closed in the manner described may be opened by punching a hole in the cover, or inserting a sharp tool between the cap and the rim around the mouth of the receptacle so as to admit air to the interior, or by prying the cover upwardly.

The invention claimed is;

1. The combination with a receptacle having a shoulder in the interior around the wall near the mouth of the receptacle, of a cover having a shoulder on the exterior around the edge near the inner face of the cover, and a gasket closely fitted against the shoulder on the cover and having flexible projections on its outer edge that are adapted when the cover is loosely placed in the mouth of the receptacle to rest upon the shoulder in the interior and support the cover with spaces between the gasket and the wall of the mouth of the receptacle until pressure is applied to the outside of the cover.

2. The combination with a receptacle having an annular recess around the interior near its mouth, of a cover having an an-

nular recess around its periphery, and a flexible gasket fitting the recess in the cover and provided with transverse grooves in its periphery and with a yielding corner adapted when the cover is loosely placed in the mouth of the receptacle to rest upon the wall of the recess in the receptacle.

3. The combination with a receptacle having an annular recess around the interior near its mouth, of a cover having an annular recess around its periphery, and a flexible gasket fitting the recess in the cover and provided in its periphery with shallow transverse grooves that are narrow at the top and wider at the bottom and with a yielding corner adapted when the cover is loosely placed in the mouth of the receptacle to rest upon the wall of the recess in the receptacle.

4. The combination with a receptacle having a concave recess around its interior, of a cover having a concave recess around its periphery, and a flexible gasket fitting the recess in the cover and provided with transverse grooves in its outer edge and with a yielding corner adapted when the cover is loosely placed in the mouth of the receptacle to rest upon the wall of the concave recess in the receptacle.

5. The combination with a receptacle having an interior shoulder around the wall near its mouth, of a cover having a recess around its periphery, and a flexible gasket fitting the recess in the cover, said gasket being provided with transverse grooves in its periphery and adapted when the cover is loosely placed in the mouth of the receptacle to rest upon the shoulder near the mouth of the receptacle in such manner that the grooves are open until pressure is applied to the outside of the cover.
